EUGENE SCHWARTZ, OF PHILADELPHIA, PENNSYLVANIA, ASSIGNOR TO KETTERLINUS
LITHOGRAPHIC MFG. CO., A CORPORATION OF PENNSYLVANIA

DISPLAY DEVICE

Application filed March 11, 1931. Serial No. 521,740.

This invention, generally stated, relates to display devices and has more particular relation to a display device constructed of thin sheet material as cardboard for retaining for inspection purposes means symbolic of an article of manufacture.

The leading object of the present invention may be said to reside in the provision of a display device of the character stated which may be supported in easel fashion or suspended for advertising purposes and which may be inexpensively manufactured.

A further object of the present invention is to provide a device of the character stated constructed of cardboard and substantially cut-away centrally thereof for the acceptance of a member symbolic of an article of manufacture, which member is enveloped in a transparent, film-like covering.

A still further object of the present invention is to provide a display device of the character stated comprising a cardboard backing suitably supported, which backing is centrally apertured to receive in nested relation a member of tray-like configuration enveloped in a transparent, film-like covering in which the nested parts penetrate the apertured portion of the backing and are attached with respect to the rear of the backing.

A still further object of the present invention is to provide a device of the character stated in which a cardboard backing is provided centrally apertured to receive nested parts depicting an article of manufacture, and in which the nested parts are secured with respect to the backing to provide a unitary structure.

A still further object of the present invention resides in the provision of general details of construction, arrangement, and combination of parts for effecting the results sought by the foregoing objects.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in perspective of the display device embodying the invention;

Fig. 2, is a view in vertical section illustrating the parts shown in Fig. 1;

Fig. 3, is a rear view of Fig. 2;

Fig. 4, is a view of a blank illustrating the tray-like member prior to being folded; and

Fig. 5, is a view similar to Fig. 4 and illustrating the blank employed for forming the envelope for the tray-like member.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 10 designates a thin, substantially flat member, preferably of cardboard or other inexpensive material, which is substantially centrally apertured or cut-away entirely therethrough, as best seen in Fig. 2, as at 11. This part 10 constitutes the body or backing of the display device, and is usually of integral structure.

Fitted to the aperture 11 of the body or backing 10 is an arrangement of parts symbolic of an article of manufacture. This device is in two parts, having nested relation, as clearly shown in Fig. 2. These two parts comprise a substantially tray-like member 12 of cardboard and a transparent, film-like envelope 13, usually cellophane.

In forming the parts 12 and 13 I make use of a cardboard blank 14, and a blank 15 of cellophane, see Fig. 5, it being understood that the blank 15 is slightly larger than is the blank 14. In practice the blank of cellophane is positioned over the blank 14 of cardboard so that the cellophane covering appears upon the face of the body or backing 10.

Both the blanks 14 and 15 are scored as at 17 and 16. The two blanks 14 and 15 are first folded along the weakened lines 17 to provide a dished or tray-like arrangement of

100

parts, as clearly shown in Fig. 2. By thus folding the blank 14, flaps 18 are provided, which flaps are passed through the aperture 11 of the body or backing so that said flaps extend entirely through the body or backing. 5 These flaps 18 are then folded back along the scored or weakened lines 16 in parallelism with the rear face of the body or backing 10, and are secured with respect to the body or backing preferably by means of an adhesive, although other means of attachment may be provided. In the connection it will be understood that the marginal edges of the cellophane covering lie between the rear face of the body or backing 11 and the inner faces 10 of the flaps of member 12, and all of these flaps are adhesively secured with respect to the rear face of the body or backing. The tray-like member 12 upon its outer faces has 15 depicted thereon suitable advertising matter to symbolize an article of manufacture, as for instance a package of cigarettes or other commodity. The cellophane covering being transparent permits visualizing of the symbolized article of manufacture and makes for a very attractive display device. The body or backing 10 is preferably supported by an easel-like arrangement of parts comprising a cardboard or equivalent member stamped 20 from a single blank and comprising a vertically disposed member 19 which has struck out therefrom at right angles thereto wings 20 arranged to be adhesively secured to the rear face of the body or backing 10. Intermediate of its height the member 19 is cut-away as at 21 so as to lie free of the folded over and secured flaps 18, as is best seen in 25 Fig. 3.

What I claim is:

1. A display device of the character stated, comprising a cardboard member constituting a body having a substantially central cut-away portion therethrough, a second member formed from a single blank of cardboard having flaps arranged to be passed through said cut-away portion and having their free ends folded over upon the body back and secured thereto, said second member depicting an article of manufacture, and a thin, film-like sheet entirely enveloping said depicted article of manufacture and having its marginal edges secured between said body and flaps. 5

2. A display device of the character stated, comprising a cardboard member constituting a body having a substantially central cut-away portion therethrough, a second member formed from a single blank of cardboard having flaps arranged to be passed through said cut-away portion and having their free ends folded over upon the body back and secured thereto, said second member depicting an article of manufacture, and a thin film-like sheet formed from a single blank slightly larger in dimensions than said first men- 10

tioned blank and entirely enveloping said depicted article of manufacture and having its marginal edges secured between said body and flaps. 15

3. A display device of the character stated, 70 comprising a cardboard member constituting a body having a substantially central cut-away portion therethrough, a second member formed from a single blank of cardboard having flaps arranged to be passed through said cut-away portion and having their free ends folded over upon the body back and secured thereto, said second member depicting an article of manufacture, and a thin film-like sheet entirely enveloping said depicted article of manufacture and having its marginal edges secured between said body and flaps, the combined parts forming a unitary structure. 75

4. A display device of the character stated, 80 comprising a cardboard member constituting a body having a substantially central cut-away portion therethrough, a second member formed from a single blank of cardboard having flaps arranged to be passed through said cut-away portion and having their free ends folded over upon the body back and secured thereto, said second member depicting an article of manufacture, and a thin film-like sheet entirely enveloping said depicted article of manufacture and having its marginal edges secured between said body and flaps, and means for supporting said body. 90

5. A display device of the character stated, 95 comprising a cardboard member constituting a body having a substantially central cut-away portion therethrough, a second member formed from a single blank of cardboard having flaps arranged to be passed through said cut-away portion and having their free ends folded over upon the body back and secured thereto, said second member depicting an article of manufacture, a thin film-like sheet entirely enveloping said depicted article of manufacture and having its marginal edges secured between said body and flaps, and a support for said body which support is cut-away adjacent that part thereof which fits over said flaps. 100
